UNITED STATES PATENT OFFICE.

JOHN S. ROBLIN, OF DETROIT, MICHIGAN.

DESIGN FOR A PAIL-COVER.

SPECIFICATION forming part of Design No. 35,560, dated January 7, 1902.

Application filed November 25, 1901. Serial No. 83,665. Term of patent 14 years.

To all whom it may concern:

Be it known that I, JOHN S. ROBLIN, a citizen of the United States, residing at Detroit, in the county of Wayne and State of Michigan, have invented and produced a new and original Design for a Pail-Cover, of which the following is a specification, reference being had therein to the accompanying drawings, in which—

10 Figure 1 is a perspective view, and Fig. 2 is a central section.

A is a funnel-shaped portion provided with a flat bottom *a* and having the appearance of a hollow truncated cone.

15 *b* is a rounded bead forming the edge of the portion A, and *c* is a second bead surrounding the cone approximately midway between its base and summit.

d is a perforated central portion of the bottom *a*.

B is a dished flange surrounding said cone adjacent to said bead *c* and curving downward therefrom, being provided with a marginal outwardly-projecting portion C and downwardly-projecting portion D. ²⁵

The leading feature of the design is the appearance of a hollow truncated cone penetrating an oppositely-dished flange.

What I claim as my invention is—

The design for a pail-cover, substantially as shown and described. ³⁰

In testimony whereof I affix my signature in presence of two witnesses.

JOHN S. ROBLIN.
